raison sociale Michelin & Cie, Clermont-Ferrand, Puy-
de-Dome, France

Filed May 19, 1969, Ser. No. 17,197

Term of patent 14 years

Int. Cl. D12—14

U.S. Cl. D90—20

FIG. 1

FIG. 1 is a perspective view of a tire showing the new design, it being understood that the tread portion shown is repeated throughout the circumference of the tire and that the shoulder design shown is repeated throughout the circumference of the shoulder, the opposite side of the tire being substantially like the side shown;

FIG. 2 is a fragmentary development plan view of the tread and shoulder portions of the tire shown in FIG. 1, the view being on a larger scale than FIG. 1; and

FIG. 3 is an axial sectional view taken through the tire substantially on the plane indicated by the line 3—3 of FIG. 2.

I claim:

The ornamental design for a tire, substantially as shown and described.
